Int. Cl. D17—01
U.S. Cl. D56—9

FIG. 1 is a fragmentary left end, front and bottom perspective view of a switch unit for use with a piano keyboard, showing my new design, the portion between the ninth and nineteenth key from the left as shown in FIG. 2 being broken away and omitted for convenience in illustration;

FIG. 2 is a front elevational view;

FIG. 3 is a top plan view;

FIG. 4 is a rear elevational view;

FIG. 5 is a bottom plan view;

FIG. 6 is a left end elevational view; and

FIG. 7 is a right end elevational view thereof.

I claim:

The ornamental design for a switch unit for use with a piano keyboard, as shown and described.
